United States Patent Office

Des. 218,731

Patented Sept. 22, 1970

218,731

BOTTLE

Kathleen Eisermann, Warren, Ohio, assignor to Andrew Matyas, Warren, Ohio

Filed May 13, 1969, Ser. No. 17,139

Term of patent 14 years

Int. Cl. D9—01

U.S. Cl. D9—63

FIG. 1 is a top plan view of a bottle, showing my new design;

FIG. 2 is a front elevational view;

FIG. 3 is a perspective view showing the back of the bottle; FIG. 4 is a sectional view on a reduced scale taken on the line 4—4 of FIG. 1.

I claim:

The ornamental design for a bottle, substantially as shown.
